UNITED STATES PATENT OFFICE.

VALENTIN CONSTANT TENEAU, OF NEW YORK, N. Y.

APPARATUS FOR DRYING PHOTOGRAPHIC PRINTS OR THE LIKE.

1,227,092.

Specification of Letters Patent.

Patented May 22, 1917.

Application filed August 14, 1916. Serial No. 114,848.

To all whom it may concern:

Be it known that I, VALENTIN CONSTANT TENEAU, a citizen of the Republic of France, residing at New York, county of New York, 5 and State of New York, have invented certain new and useful Improvements in Apparatus for Drying Photographic Prints or the like, of which the following is a specification, reference being had therein to the accompanying drawing.

The invention relates to improvements in apparatuses for drying sheet materials, and more particularly to that type of such apparatuses which are adapted for the drying 15 of photographic prints or the like.

The main object of the invention is to provide a machine of the character mentioned, and one of a comparatively inexpensive and simplified construction, wherein extreme rapidity of operation is obtained with a minimum possibility of injury to the sheets in their passage through the heating zone of the machine.

With this and other objects in view, the 25 invention resides in the certain new and useful construction as will be hereinafter more fully described, set forth in the appended claims, and illustrated in the accompanying drawings, in which,

30 Figure 1 is a top plan view of the apparatus,

Fig. 2 is a side elevation,

Fig. 3 is a side elevation opposite to that shown in Fig. 2,

35 Fig. 4 is a front elevation,

Fig. 5 is a vertical longitudinal section on the line 5—5 of Fig. 1, and,

40 Fig. 6 is a fragmentary sectional detail of one of the drum heating burners, its connections to the fuel supply pipe, and of one of the end walls of a heating drum.

Reference being had to the drawings, in which similar characters of reference designate corresponding parts in the several views 45 thereof, the apparatus comprises a supporting frame formed preferably of a plurality of pipe sections suitably coupled together to provide vertically disposed side sections or standards 10, 11, 12 and 13, horizontally dis-

posed side sections or members 14, 15, 16 and 50 17, and horizontal transversely disposed end sections or members 18 and 19, the vertically disposed side sections or members 11 and 13 being of greater length than that of the side sections 10 and 12 and projecting above the 55 plane of the top horizontal sections or members 16 and supporting on their projected ends the top horizontal sections or members 17.

A main heating drum 20 is disposed transversely of the rear part of the frame and is supported for rotation at the lower part of the latter on a stationary tubular section 21, which is supported at its opposite ends in suitable couplings 22 forming a part of horizontal connecting sections or members 23, the latter being connected to and extending between the vertical side sections or members 12 and 13 of the frame. Immediately above the main heating drum 20, and offset at opposite sides thereof, is arranged a pair of spaced heating drums 24 and 24', the same being each relatively of less diameter than that of the drum 20. The drum 24' is rotatably mounted on a fixed or stationary tubular member 25, which is supported at its opposite ends from the vertical side sections or members 12, and the drum 24 is similarly mounted on a fixed tubular member 26 extending between the opposite side sections 80 13, of the frame. A pair of rollers 27 and 28 are journaled, respectively, between the lower ends of the vertical sections 12 and 13. A roller 29 is supported between the intermediate portions of the sections 11, and 85 is preferably mounted for rotation in slideable bearing sleeves 30, which may be held in adjusted position by means of set screws 31, or in any other suitable manner. Another roller 32 is supported between the horizontal 90 sections 16, at the forward part thereof, and are also mounted for rotation in slideable bearings 33, which are adapted to be retained in adjusted position by means of set screws 34. An endless belt or web 35 is trained 95 over the roller 32 and extends horizontally therefrom and passes over the heating drum 24', downward to and around the main heat-

ing drum 20, upward and over the heating drum 24, downward and around the roller 28, under and around the roller 27, upward, in an inclined direction, to and over the adjustable roller 29, and from thence to and around the adjustable roller 32. A second endless belt or web 36 is trained over the heating drums 20, 24 and 24', and contacts the belt or web 35 throughout its travel over the latter, and passes from the adjacent surfaces of the drums 24 and 24' in opposite directions and over a fixed roller 37 and an adjustable roller 38, the latter being rotatably mounted in slideable bearing sleeves 39 which are supported on the horizontal section 17, of the frame, and in alinement with the fixed roller 37, which is journaled in the couplings connecting the vertical sections 13 with the horizontal sections 17.

20 A fuel supply pipe 41, leading to a fuel source (not shown), is provided with branch connections 42 and 43, which lead, respectively, to the tubular members 25 and 26, forming the supports or shafts of the drums 24' and 24 respectively, and which connections 42 and 43 are each provided with a control valve 44. A third branch pipe 45 connects with a valved inlet, formed with the coupling 22, through which fuel is admitted to the tubular member 21, forming the supporting shaft for the drum 20. The tubular members or shafts 21, 25 and 26 are each provided with sets of conical openings 46 for the ignition and combustion of the fuel passing therethrough.

To regulate the temperature within the drums 20, 24 and 24', each of the latter is formed with end walls having a plurality of openings, and are provided with rotatable plates 48 having a corresponding number of openings 49, which are adapted to be moved into and out of alinement with the first mentioned openings (not shown), as may be desired, a finger grip 50 being provided on the plates 48, whereby the same may be readily operated, and the latter are preferably formed with one or more curved slots 51 arranged to cooperate with pins 52, carried by the end walls 47 of the drums, for limiting the movement of the plates in either direction.

For the operation of the drums and the conveyer belts or webs trained thereover, power is applied to the main heating drum 20 by means of a pulley 53 and a belt 54, the latter connecting the former to the pulley of a suitable source of power, as for instance, an internal combustion engine 55, which is supported upon a bed-plate 56 suitably secured in proper position on the oppositely disposed lower horizontal sections 14, of the frame, and at the forward part of the latter, immediately below the horizontal travel of the belt or web 35.

In the operation of the apparatus, power 65 being applied to the main heating drum 20, and the fuel ignited at the sets of openings of one or more of the tubular members 21, 25 and 26, of the drums 20, 24' and 24, the sheet material or articles are laid on the 70 horizontally disposed portion of the belt or web 35, at the forward end of the machine, and are carried forward thereon and pass in between the latter and the belt or web 36 to the point of discharge at the rear of the 75 machine, where the sheets are to be collected, or are allowed to stack up in a suitable receptacle supported in proper position from the rear vertical sections 13 of the frame.

The heating drums 20, 24 and 24' may, if 80 desired, be covered with a felt, or similar material to prevent injury to the belts or webs, and consequently to the sheets carried by the latter in their passage over the surfaces of the drums.

Having thus described the invention, and its operation, it is to be fully understood that various changes in the detailed construction and arrangement of the parts thereof may be resorted to without departing from the 90 spirit and scope of the same.

Having thus fully described the invention, what is claimed, is:

1. A drying apparatus for sheet materials comprising a frame, a plurality of heating drums carried by said frame, burners extending through each of said drums and supported from said frame, means for regulating the fuel supply to said burners, means for regulating the temperature of said drums, endless webs trained over said drums and contacting each other for a portion of their length, means for tensioning said webs, and means for rotating said drums for the actuation of said webs to convey the sheets to be dried over the heated surfaces of said drums.

2. A drying apparatus for sheet materials comprising a frame, a plurality of heating drums carried by said frame, burners extending through each of said drums and supported from said frame at their opposite ends, said burners forming bearings for said heating drums, means for regulating the temperature of said heating drums, endless web conveyers trained over said heating drums and contacting each other for a portion of their length, means for tensioning said web conveyers, and power means for the rotation of said heating drums for the actuation of said conveyer webs and the sheets carried thereby.

3. A drying apparatus for sheet materials comprising a frame, a main heating drum, a pair of smaller heating drums disposed in a plane immediately above said main heating drum and offset to either side thereof, burners extending through said heating

drums and supported from said frame at their opposite ends, said burners forming bearings for said drums, means for regulating the temperature of said heating drums, 5 endless web conveyers trained over said heating drums and contacting each other for a portion of their length, means for tensioning said web conveyers, and power means for the rotation of said heating drums for the

actuation of said web conveyers and the 10 sheets carried thereby.

In testimony whereof I affix my signature in the presence of two witnesses.

VALENTIN CONSTANT TENEAU.
